Primary Examiner — Mary Ann Calabrese(74) *Attorney, Agent, or Firm* — Workman Nydegger(57) **CLAIM**

The ornamental design for a pillow, as shown and described.

DESCRIPTION

FIG. 1 is a front perspective view of a pillow;
FIG. 2 is a top view of the embodiment of FIG. 1;
FIG. 3 is a bottom view of the embodiment of FIG. 1;
FIG. 4 is a front elevation view of the embodiment of FIG. 1;
FIG. 5 is a rear elevation view of the embodiment of FIG. 1;
FIG. 6 is a right elevation view of the embodiment of FIG. 1; and,
FIG. 7 left elevation view of the embodiment of FIG. 1;
In the drawings, the broken lines illustrate portions of the
pillow that form no part of the claimed design.

1 Claim, 5 Drawing Sheets(56)
